AIR CONDITIONING APPARATUS

William S. Somers, Columbus, Ohio

Application June 22, 1938, Serial No. 215,254

4 Claims. (Cl. 126—101)

This invention relates to air conditioning apparatus of the type adapted for controlling the temperature and other properties of atmospheres prevailing in residence or building rooms, or other wall-confined areas.

In certain of its more specific aspects, the invention provides a heating system for residences and other purposes wherein forced circulation of conditioned air is provided in combination with steam or hot water heated radiator units.

In most of the forced air house heating systems commercially available at present, solid or fluid type fuels are burned to generate hot gases which are directed against the internal walls of heat exchangers and ultimately pass to the atmosphere, the air to be heated being forced or drawn over the outer walls of such exchangers by passage through a confined casing, so that the air is thereby heated to required temperatures for room delivery and passed through associated ducts or conduits to the rooms under temperature control. Most of these systems, operating under automatic or thermostatic regulation, provide intermittent high and low stage operations. During high stage operation, the fuel burners are operated at maximum capacity to quickly heat the walls of the heat exchangers in order to satisfy the heat requirement as rapidly as possible, after which the burners are shut down to low stage or pilot operation until a heat demand is again presented. These alternate requirements for quickly developed high stage operation result in considerable fuel waste and produce an undesired variation in temperature of the room atmospheres in the intervals between high and low stage operation.

Steam and hot water systems of the radiator type have had long and successful use in residence and building applications, producing a high degree of warmth with economical fuel consumption. However, these latter systems require the placing of radiators in the individual rooms to be heated together with associated piping and control valves leading from the furnace or boiler, with the result that the same are not adaptable in general to the more modern forced air types of heating systems wherein room radiators are eliminated.

It is, therefore, a leading object of the invention to incorporate in a modern forced air heating system a centrally disposed heating unit of the boiler-radiator type, wherein the radiator or radiators is located in the same general casing as the boiler or combustion unit, and wherein provision is made for forcing air to be heated

over the radiator or radiators and thence through associated conduits to the various spaced points of room delivery, this system making possible the use of the economical and efficient hot water or steam heating units and the minimizing of temperature differentials in the rooms under heat control.

Another object of the invention is to provide a heating system wherein a centrally disposed heater is used consisting primarily of a fuel-fired boiler or steam generator which is arranged within a casing having communicating air inlet and discharging chambers, the boiler or generator having its water drum connected with a heat exchanger of the radiator type also mounted within in said casing and so disposed that thermal circulation of hot water or steam from the drum of the generator to the radiator is provided, provision being made in the system to effect the forced passage of air to be heated over the outer surfaces of the radiator and thence to the rooms to be heated, together with the return and filtration of the air following cooling thereof to the inlet chamber of the casing prior to the re-passage of such air over the radiator.

A further object of the invention resides in the provision of a heating or air conditioning system which is essentially simple and economical in its design and operation and which may be readily installed with a minimum of labor and expense in practically all types of residential and other buildings.

The present application is a continuation-in-part of my prior co-pending application, Serial No. 149,609, filed June 22, 1937.

The above and other objects will be made more apparent by the following description and the accompanying drawings, which show the invention in several of its different mechanical forms, and, wherein:

Fig. 1 is a vertical sectional view taken through the improved heating apparatus comprising the present invention;

Fig. 2 is a vertical transverse sectional view taken through the apparatus on the plane indicated by the line II—II of Fig. 1;

Fig. 3 is a top plan view disclosing the casing and plenum housing of the heating apparatus;

Fig. 4 is an enlarged vertical sectional view taken through the plenum housing and also disclosing the radiator section of the heating system;

Fig. 5 is a horizontal sectional view taken on the plane indicated by the line V—V of Fig. 4;

Fig. 6 is a similar horizontal sectional view as

Fig. 5, but disclosing an alternative arrangement of the dividing walls of the plenum;

Fig. 7 is a detail horizontal sectional view on the line VII—VII of Fig. 5 and disclosing the heat insulating jackets for the boiler or steam generator;

Fig. 8 is an enlarged vertical sectional view illustrating the joints uniting communicating sections of the air discharging conduit of the heater casing, the plane of the figure being indicated by the line VIII—VIII of Fig. 1;

Fig. 9 is a similar view on the line IX—IX of Fig. 8;

Fig. 10 is a vertical sectional view through a modified form of heater casing wherein the boiler or steam generator is disposed in a separate chamber of the casing assembly;

Fig. 11 is a sectional view of a further modified form of the present invention wherein a single boiler or steam generator is employed to supply a heated fluid to a multiplicity of spaced radiators, as in apartment house installations wherein individual control for each apartment is required with the use of a central heating unit.

Fig. 12 is a further modified form of the invention wherein the heat exchanger is arranged in both the return air and outgoing air compartments of the plenum housing of the heater casing.

Referring more particularly to the drawings, and especially to the form of the present invention illustrated in Figs. 1 to 9 inclusive thereof, the numeral 1 designates the outer casing of my improved heating apparatus. This casing may be formed from sheet metal of relatively thin gauge and does not require in its wall construction the use of heat insulating materials. The exterior surfaces of the casing 1 may be finished or ornamented in any desired manner in order to present an attractive appearance. Ordinarily, the casing 1 is disposed in the cellar, basement or furnace room of a residence or other building, and because of its attractive external appearance, the same does not in any way detract from the setting it may occupy.

Within the casing, there is arranged a refractory furnace box 2 having a combustion chamber 3. Any suitable type of fuel may be burned within this chamber, either solid or fluid. In the present instance, however, an automatic hydrocarbon fluid burner has been indicated at 4, with its burner discharge pipe 5 entering the chamber 3, the burner as a whole being arranged within a compartment 6 formed in the lower right hand corner of the casing 1 (see Fig. 1). Air for the operation of the burner 4 enters the casing by way of the opening 7, which is normally closed by means of a screen or its equivalent 8. The combustion gases, generated in the chamber 3, are utilized to heat a water boiler or drum 9 in order to effect the development of steam and, following desired contact with the surfaces of the boiler, the combustion gases are discharged to the atmosphere through a duct 10, leading to a chimney or other form of outlet stack, not shown. If desired, the boiler or drum may be surrounded by a radiation control wall or jacket 9a, as shown in Fig. 7. This wall is provided to prevent the cool air entering the casing 1 from directly contacting the boiler wall and preventing efficient steam generation. As shown in Fig. 1, the jacket 9a may be formed with a plurality of perforations to allow a limited circulation of air between the jacket and the boiler walls, the quantity of air

admitted being controlled by the number and size of the openings.

The steam or hot water outlet of the boiler or drum 9 is connected by means of piping 11 with the upper manifold 12 of a stationary heat exchanger in the form of a substantially horizontally disposed radiator 13. The latter, in this instance, comprises the upper manifold 12 and a parallel somewhat lower outlet manifold 14, the two manifolds being connected by means of a plurality of spaced parallel, transversely extending tubes 15 of considerably smaller diameter than said manifolds, and heat radiating fins 16 are joined with the tubes 15 and extend transversely thereof in parallel spaced relationship 15 with one another.

The outlet manifold 14 has its opposite ends connected with return piping 17 which leads to the bottom of the drum or boiler 9, in order that the cold or condensed heating fluid may be returned to said boiler or drum for reheating. Also, a pressure balancing pipe 18 unites the piping 11 with the return piping 17 immediately ahead of the point of entry of the latter into the bottom of the boiler drum. By this arrangement, thermal circulation of the heating fluid is automatically maintained with but a minimum of equipment and without the use of special injector means for the return of feed water leading to the boiler.

Mounted on top of the casing 1 is a plenum housing 19. Preferably, this housing includes rectangular and vertical side walls 20 and a horizontal top wall 21. As shown in Figs. 5 and 6, the walls 20 have their vertical edges terminated in inwardly extending adjoining flanges 22, which are welded or otherwise secured together. These flanges act as guide ribs for the reception of the outer vertical edges of a pair of removable divisional plates 23—23. The side walls 20 of the housing 19 are formed with openings 24 reinforced by angular frames 25. Connected with the frames 25 are air inlet or return conduits 26 and, with other sides of the housing, air outlet or discharge conduits 27. By the removal of the top wall 21, it will be seen that the plates 23 may be adjusted to assume different positions in the plenum housing.

In the arrangement disclosed in Fig. 5, the plates 23 are positioned so that the discharge conduits 27 for the passage of heated air are arranged at the right and left of the figure, with the cool air returns 26 at the top and bottom thereof, whereas in Fig. 6, the said plates 23 are positioned so that the conduits 26 for the discharge of warm air are situated at the top and at the right side of the figure and the return conduits 26 for the cool air at the left and bottom portions of the figure. This arrangement provides very considerable flexibility in the matter of heater casing installation and enables the conduits 26 and 27 to be disposed wherever most advantageous, depending upon the physical conditions present in the room in which the heater casing is located and with respect to the position which the heater casing is to occupy in said room, the arrangement avoiding the crossing of the ducts, avoids interference with head room in a low ceiling basement or cellar, and also enables the ducts to be concealed to advantage between floor supporting joists or the like.

As shown in Fig. 5, cool air returning from the rooms of a building heated by the apparatus, enters the compartments 28 of the plenum housing and passes downwardly through the open

bottom of these compartments into the interior of the casing 1, passing freely around the piping 11, 17 and 18, the outer portions of the drum 9 and the duct 10, absorbing any heat which may be released from the surfaces of these elements. The return air thus drawn into the casing is then passed through one or more filter elements 29, composed of glass wool, or other equivalent material, by which fine solids, carried in suspension in the returned air, may be caught in the strands of the filter and permanently trapped thereby. The filtered air is then delivered into a chamber 30 and enters the suction side of a blower or fan 31 operated by an electric motor 32. From the discharge side of the blower or fan 31, a vertical upwardly extending conduit section 33 leads the air in a confined stream in an upward direction, the section 31 terminating at its upper end in outturned flanges 34 which, as shown in Figs. 8 and 9, are joined with complementary flanges 35 provided on the lower edges of an angularly directed conduit section 36 which opens at its upper end into the central compartment 37 of the plenum housing, this compartment being in open communication with the warm air discharge ducts or conduits 27. Also situated in the upper portion of the duct section 36 is the radiator or heat exchanger 13. As the air advanced from the fan or blower through the conduit sections 33 and 36 contacts with the highly heated exterior surfaces of the radiator, including its manifolds 12 and 14, tubes 15 and fins 16, the air is heated to the required temperature suitable for room heating.

In view of the foregoing, it will be seen that the present invention provides a forced air heating system which utilizes a boiler-radiator heating element and thus incorporates in a forced air heating system the economies and sustained heat continuity inherent in the water vapor radiator type of heating system. The units of such a system are enclosed in a single centrally situated casing so that they do not take up space in the rooms of a building and, moreover, are out of sight. The arrangement permits of the use of the relatively small cross-sectional conduits now used in forced air heating systems and the correspondingly small inlet and outlet registers in the room walls. Aside from operating economy and simplicity, the outstanding advantage of the water vapor radiator type of heating element is the remarkable uniformity of room temperatures over prolonged periods of time, it being possible with the use of this system to hold room temperatures between limits of but a few degrees of variation.

In the modified form of the invention illustrated in Fig. 10, the casing 1a is provided internally with a divisional wall 40, which provides separate compartments 41 and 42 for the reception of the boiler or steam generator and the the air distributing and controlling elements, respectively. In the form of the invention illustrated in Fig. 11, the heat exchanger or radiator and the air circulating units are disposed in a casing 45 which is separate and spaced from the generator or boiler 9. Installations of this kind are highly practicable for use in apartment buildings or the like, where it is desired to provide separate control for the heating of each individual apartment with a common boiler or steam generator for all of the units 45. In Fig. 11, a steam supply pipe 46, leading from a suitable source of steam generation enters the casing 45 and is connected with the radiator unit disposed therein. The pipe 46 is provided with a

control valve 47 by means of which the steam supply to the radiator unit may be shut off. This enables the unit to be used for air cooling purposes, since it is possible to circulate a refrigerant therethrough wherein the refrigerant is supplied by a pipe line 48, valved as at 49, and connected with the pipe 46 on the radiator side of the control valve 47. The return pipe 50 leading from the radiator unit of Fig. 11 extends back to the steam generator or by means of a shunt line 51 to the source of refrigerant supply. Control valves 52 and 53 are provided in the lines 50 and 51 respectively. The casing 45 includes filters 54 and a motor driven fan or blower 55. The casings 45 are comparatively small and compact and will occupy but a minimum of room in an apartment, or they may be placed at any other convenient point in an apartment building.

In Fig. 12, the heat exchanger or radiator 13, instead of being located only in the air discharging compartment of the plenum housing, as shown in the preceding figures of the drawings, is extended so that portions thereof will be disposed in the receiving or return air compartments of the plenum housing, as indicated at 13a. Such an arrangement permits the air returning to the heater casing to be preheated prior to its passage through the fan or blower 31. It will be understood that it is within the scope of the invention to circulate a cooling fluid through the heat exchanger in periods of warm weather if it should be so desired.

What is claimed is:

1. In air conditioning apparatus, a heating unit comprising a casing divided internally into inner and outer chambers, steam generating means positioned in said outer chamber, a heat exchanger disposed in said inner chamber, said exchanger being in communication with said generator, a manifold provided at the top of said casing, partition means separating said manifold into warm and cool air sections, the former communicating with said inner chamber and the latter with said outer chamber, and a motor driven blower positioned at the inlet to said inner chamber, the inlet to said blower being in open communication with said outer chamber.

2. In air conditioning apparatus, a heating unit comprising a casing divided internally into inner and outer chambers, steam generating means positioned in said outer chamber, a heat exchanger disposed in said inner chamber, said exchanger being in communication with said generator, a manifold provided at the top of said casing, partition means separating said manifold into warm and cool air sections, the former communicating with said inner chamber and the latter with said outer chamber, a motor driven blower positioned at the inlet to said inner chamber, the inlet to said blower being in open communication with said outer chamber, and means for filtering the air prior to its entrance into said blower.

3. In air conditioning apparatus, a heating unit comprising a casing divided internally into inner and outer chambers, steam generating means positioned in said outer chamber, a heat exchanger extending across said inner chamber, said exchanger being in communication with said generator, a manifold provided at the top of said casing, partition means separating said manifold into warm and cool air sections, the former communicating with said inner chamber and the latter with said outer chamber, and a motor driven blower positioned at the inlet to said inner chamber.

ber, the inlet to said blower being in open communication with said outer chamber.

4. In air conditioning apparatus, a heating unit comprising a casing, a manifold provided at the top of said casing, partition means separating said manifold into warm and cool air sections, a hollow substantially vertically extending column provided in said casing, the upper end of said column communicating with the warm air section of said manifold, the cold air section of the manifold being in open communication with the interior of said casing, a steam generator

position in said casing, a heat exchanger extending transversely of said column, means for connecting said heat exchanger with said generator, a motor driven blower having the outlet thereof connected with the lower end of said column, the inlet of said blower being in open communication with the interior of said casing, and an air filtering partition extending across said casing between the inlet to said blower and said generator.
